THERMALLY CONTROLLED SWITCH

Joseph F. Frese, Baltimore, Md., assignor to
Monitor Controller Company, Baltimore, Md.,
a corporation of Maryland

Application September 26, 1934, Serial No. 745,625

12 Claims. (Cl. 200—122)

This invention relates to a thermally operated circuit controlling device and particularly to compensating thermally responsive elements which will operate the controlling device the same under identical operating conditions irrespective of changes in atmospheric temperatures. The type of thermally responsive element to which the present invention relates generally is that shown in the patent granted May 10, 1927, to George H. Whittingham, No. 1,627,816 for Thermal limit relay, comprising a tubular housing composed of a flat-bimetallic strip wound into the form of a helix arranged vertically with its lower end open and secured to a suitable support and its upper end closed and free to turn. A heating element, comprising a part of a circuit, the flow of current in which is adapted to control the switch of the device, is inserted into the housing through its lower end, and the heat generated by the current in the heating element causes the housing to partially uncoil to operate the switch. Such a thermally responsive element is caused to operate, more or less, by the temperature of the surrounding air and in order to compensate for changes therein, the present invention contemplates interposing a second thermally responsive element between the current heated one and the switch which element is subject to only the air temperature, and changes in response thereto in an opposite sense to the first element.

For a full understanding of the invention, reference may be had to accompanying drawing and following specification, wherein is disclosed a single exemplary embodiment of the invention with the understanding that such changes may be made therein as fall within the scope of the appended claims without departing from the spirit of the invention.

40 In said drawing;

Fig. 1 is a front elevation of an apparatus constructed according to the present invention;

Fig. 2 is a right side elevation of the same;

Fig. 3 is a central vertical section of the device of Fig. 1; and,

Fig. 4 is a transverse section taken on line 4—4 of Fig. 1.

In the drawing, 10 represents a base of suitable insulating material and 11 and 12 are thermally responsive elements, each adapted to operate a circuit breaker or switch 13. These elements are alike except that being arranged on opposite sides of the circuit breaking switch, they are constructed so as to twist in opposite directions when heated to operate the switch. The

construction of both elements will be understood from a description of element 12, which comprises a tube formed from a helically coiled flat bi-metallic strip 14. The lower end of the tube, which is preferably arranged vertically by suitable mounting of the base, is open and secured as by soldering or brazing within an opening in the lower bracket arm 16 of a strap 17 secured to the base behind the tube. This fixes the lower end of the tube rigid. The upper end is closed by a permanently attached hub 15 from which extends an arm 18 carrying the insulating button 19 for operating the switch tripping mechanism. This hub is journaled on a stationary pin 20 mounted in the upper flange 21 of the strap 17 which guides the upper end of the tube but permits it to rotate by the coiling or uncoiling of the strip from which it is formed.

The heating element consisting of a wire 22 doubled upon itself and having its ends secured to binding posts 23 and 24, is passed through the aperture in bracket 16 into the interior of the tube 12. The binding posts may be included in a circuit, the current of which operates the circuit breaker.

The element 11 is identical in construction with the element 12 except that it is oppositely wound so that its button 19' is adapted to be moved in the same direction as the button 19 when its heating element, which may be in the same or a different circuit from the one in element 12, is energized. The buttons operated by the thermally responsive elements are located under furcations 25 on the end of a tripping lever a.

The tripping lever a has integral ears 27 at its 35 opposite edges which are pivoted to ears 28 extending from a strap 29 secured to the base 10. A light spring 30 between the lower end of the tripping lever and the strap 29 presses the bifurcated upper end of the lever toward the buttons 19—19'.

Any suitable form of switch mechanism may be operated by the tripping lever or directly by the thermal elements either in the arrangement shown or in other suitable arrangements. The 45 preferred switch mechanism comprises a stationary contact member 31 supported from the base 10 and a spring contact arm 32 which is secured to a cross-piece 33 on a resetting lever c. This lever comprises a sheet metal cross-piece 35 having a handle 36 secured to its central portion and having at its ends two parallel arms 37 which are pivoted to ears 38 projecting outwardly from the plate 29. The cross-piece 33 is secured to the lower edges of the arms 37 and a portion of the 50

spring contact member 32 is bent into U-form at 32' and fits around the inner edge of said cross-piece, where it is secured. The lower end 32'' of the spring member is turned downwardly 5 near the outer edge of the cross-piece 33 to form a stop for an extension of the tripping lever now about to be described.

A bi-metallic strip *b* is bent into substantially loop form and has its shorter leg 43 secured as 10 by riveting to the upper face of the tripping lever *a*. The longer leg 44 extends back over this short leg and is bent inwardly as at 45 and then upwardly to provide an end 46 which engages under the lower face of the cross-piece 33 of the re- 15 setting lever of the switch to restrain it in circuit closing position, as shown in Figs. 2 and 3. Under these conditions the under-surface of the end 46 of this bi-metallic strip rests on the stop 32''.

Under the conditions just described, if either 20 of the thermally responsive elements 11 or 12 is sufficiently heated by the passage of current through its heating coil, it uncoils and one of the buttons 19-19' engages under a limb of the tripping lever and rotates it in a counter-clockwise 25 direction as viewed in Figs. 2 and 3. This lifts the end 46 from beneath the crossbar 33 and into a position below the opening 42 between this and the crossbar 35 so that the switch now drops open by gravity to the limit permitted by the stop lugs 30 48 formed integrally with the switch frame and which engage the plate 29.

The bi-metallic strip *b* attached to the tripping lever has its two metals so selected and disposed that, with the end 46 held stationary by 35 engagement with the crossbar 33 and stop 32'', its rate of change of shape, due to variations in the temperature of the surrounding air, is such as to move the furcations 25 of the tripping lever at substantially the same rate and direction as the 40 surrounding air temperature causes the thermal elements 11 and 12 to move the buttons 19-19' so that the clearance 50 between these parts remains substantially constant. This insures that the switch will be tripped under the same operating 45 conditions at all temperatures of the surrounding air so that the same time element of operation will exist for each operating condition. The interposed thermal element *b* is remote from either of the operating elements 11-12 and hence 50 is not subject to their heating elements. It is freely exposed to the atmosphere so that its compensating changes take place with the same facility as do changes in the thermal elements 11 and 12 resulting from air temperatures.

55 What I claim is:

1. In a circuit controlling device, in combination, a switch comprising a stationary member and a movable member, a thermally responsive element adapted to actuate the movable member 60 to operate the switch, a heater for said element, and a bimetallic loop interposed between said element and movable member, said loop being spaced laterally from said element and heater so as to be subject only to atmospheric temperatures.

65 2. In a circuit controlling device, in combination, a switch comprising a stationary member and a movable member, a lever, a bimetallic loop carried by said lever and engageable with said movable member, a thermally responsive element 70 adapted to actuate said lever when heated to move the same and to thus move said loop, and a heater for said element adapted to be connected into a control circuit.

75 3. In a circuit controlling device, in combination, a switch comprising a stationary contact, a

movable member carrying a second contact for engagement with and disengagement from the first, means to maintain the second member out of normal position and including a tripping lever and a bimetallic extension thereon engageable with said member, a thermally responsive element adapted to actuate the tripping lever to disengage the extension from the member to condition it for return to normal position, and a heater for said element. 10

4. In a circuit controlling device, in combination, a switch comprising a stationary contact, a movable member carrying a second contact for engagement with and disengagement from the first, means to maintain the second member out of normal position and including a tripping lever having an operating button, a bimetallic extension on said lever engageable with said member, changes in atmospheric temperature causing changes in shape of said extension to move said lever and button, a thermally responsive element having an arm spaced from said button, and a heater for said element to cause it to distort and press the arm against the button to release the extension from the member to trip the switch. 15 20 25

5. In a circuit controlling device, in combination, a switch comprising a stationary contact, a movable member carrying a second contact for engagement with and disengagement from the first, means to maintain the second member out of normal position and including a tripping lever having an operating button, a bimetallic extension on said lever engageable with said member, changes in atmospheric temperature causing changes in shape of said extension to move said lever and button, and a heater for said element to cause it to distort and press the arm against the button to release the extension from the member to trip the switch, said bimetallic extension and said thermally responsive element being coordinated to maintain a substantially uniform spacing between said button and arm with changes in atmospheric temperature. 30 35 40

6. In a circuit controlling device, in combination, a switch comprising a stationary and a movable member, said movable member having normal and restrained positions, an elongated bimetallic strip having one end adapted to hold said member in its restrained position, a thermally responsive element, an electric heater therefor adapted to cause movement of a part of said element when energized, and means associating said part and the opposite end of said strip whereby the strip is moved to release the member 55 when the said element is heated.

7. In a circuit controlling device, in combination, a switch comprising a stationary and a movable member, said movable member having normal and restrained positions, an elongated bimetallic strip having one end adapted to hold said member in its restrained position, a thermally responsive element, an electric heater therefor adapted to cause movement of a part of said element when energized, and means associating said part and the opposite end of said strip whereby the strip is moved to release the member 60 when the said element is heated, said bimetallic strip being constructed to compensate for movement of the thermally responsive element 65 part under the action of atmospheric temperature changes, whereby actuation of the switch by the heating element is the same at all times for the same condition of heating. 70

8. In a circuit controlling device, in combina- 75

- tion, a switch comprising a stationary and a movable contact, a resetting lever for said movable contact normally holding it separated from the stationary contact, a pivoted tripping lever, a 5 thermally responsive element having a part movable to actuate said tripping lever, an electric heater for said element to cause it to move said part, a bimetallic strip extending from said tripping lever into the path of said resetting lever and 10 adapted to hold the same in switch-closing position when manually set, movement of said thermally responsive element part serving to move said strip to trip the resetting lever, said strip being constructed to compensate for movements 15 of said part responsive to changes in atmospheric temperature.
9. In a circuit controlling device, in combination, a switch comprising a stationary and a movable contact, a resetting lever for said movable contact normally holding it separated from the stationary contact, a pivoted tripping lever, a thermally responsive element having a part normally spaced from and movable to actuate said tripping lever, an electric heater for said 20 element to cause it to move said part to close said space and move said lever, a bimetallic strip extending from said tripping lever into the path of said resetting lever and adapted to hold the same in switch closing position when manually 25 set, movement of said thermally responsive element part serving to move said strip to trip the resetting lever, said strip being constructed to compensate for movements of said part responsive to changes in atmospheric temperature to 30 maintain said space substantially constant.
10. In a circuit controlling device, in combination, a suitable base, a stationary contact thereon, a resetting lever pivoted to said base, a contact on said lever out of engagement with the first 35 contact when the lever is in its normal position and engaging the first contact when the lever is in a restrained position, a pivoted tripping lever, a thermally responsive coil having a part normally spaced from said tripping lever, an electric heater for said coil to cause it to move said part to close said space and move the tripping lever with its free end in the path of said reset- 40
- ting lever, said end being adapted to hold the resetting lever in restrained position when the same is manually set, movement of the resetting lever serving to move said strip end to trip the resetting lever, said strip being constructed to compensate for movements of said part responsive to changes in atmospheric temperature by moving the tripping lever to maintain said spacing substantially constant. 45
11. In a circuit controlling device, in combination, a suitable base, a stationary contact thereon, a resetting lever pivoted to said base, a contact on said lever out of engagement with the first contact when the lever is in its normal position and engaging the first contact when the lever is in a restrained position, a pivoted tripping lever, a thermally responsive coil having a part normally spaced from said tripping lever, an electric heater for said coil to cause it to move said part to close said space and move the tripping lever, a long bimetallic strip extending from said tripping lever with its free end in the path of said resetting lever, said end being adapted to hold the resetting lever in restrained position when the same is manually set, movement of the resetting lever serving to move said strip end to trip the resetting lever, said strip being constructed to compensate for movements of said part responsive to changes in atmospheric temperature by moving the tripping lever to maintain said spacing substantially constant, and a spring to bias said strip end into resetting lever restraining position. 50
12. A thermally controlled switch mechanism comprising a helix composed of a bi-metallic strip, 35 fixed at one end and having its opposite end free to turn, an arm secured to and projecting laterally from the latter end, a lever having one end in position to be engaged by said arm, a spring normally biasing said lever toward the 40 arm, a switch part, forming a stop, a bi-metallic loop having one leg thereof secured to the lever and having the free end of its other leg adapted to rest against said stop in the closed position of the switch, and a heater for said helix. 45
